[57] **CLAIM**

The ornamental design for a seat adaptable to barricades, as shown and described.

DESCRIPTION

FIG. 1 is a top, front and left side perspective view of a seat adaptable to barricades showing my new design in use, the broken line showing of a portion of a barricade is for illustrative purposes only and forms no part of the claimed design;

FIG. 2 is a left side elevational view thereof, the right side being a mirror of that shown;

FIG. 3 is a front elevational view thereof;

FIG. 4 is a top plan view thereof;

FIG. 5 is a bottom plan view thereof; and,

FIG. 6 is a rear elevational view thereof.

1 Claim, 2 Drawing Sheets
